(No Model.)

H. WORRALL.

HARMONIC DAMPER FOR PIANOS.

No. 398,924.

Patented Mar. 5, 1889.

Witnesses. *J. D. Gies.* Inventor. *Harvey Worrall*

J. D. Gies.
Henry Worrall

UNITED STATES PATENT OFFICE.

HARVEY WORRALL, OF TOPEKA, KANSAS.

HARMONIC DAMPER FOR PIANOS.

SPECIFICATION forming part of Letters Patent No. 398,924, dated March 5, 1889.

Application filed June 14, 1886. Serial No. 205,130. (No model.)

To all whom it may concern:

Be it known that I, HARVEY WORRALL, a citizen of the United States, residing at the city of Topeka, in the county of Shawnee and 5 State of Kansas, have invented a new and useful Improvement in the Arrangement and Operation of the Strings in a Piano, of which the following is a specification.

The object of my invention is to produce 10 the principal tone of a piano-string by the combination of its harmonic vibrations or by the combination of the vibrations of the aliquot parts of the string, whereby the tone is prolonged and its purity and quality improved.

The invention is illustrated in the accompanying drawings in the case of a single string, the same device being repeated in its 20 application to any and all others of the strings, as desired.

The advantages of the invention appear most prominently in the case of those tones which are now produced from the short strings, since all of these tones may with my invention 25 be produced from strings of any desired length equaling or exceeding even the length of the lowest bass tone.

Figure 1 represents the device in combination with the string and its key and hammer 30 and complementary levers when the string is silent and the mechanism at rest. Fig. 2 represents the same mechanism in its position just as the hammer is striking the string. Fig. 3 represents the harmonic vibrations produced by my invention, and Fig. 4 represents the position of the mechanism just after the hammer has struck the string and before the finger has left the key. All of the views present a side elevation of the mechanism.

40 Similar letters indicate similar parts in the several figures.

a is the key, *h* the hammer, and *L L'* the complementary levers as ordinarily constructed.

w is the string, and *b* the sounding-board.

45 My device is seen in the lever *l*, supported and operated upon the fulcrum *p*, which rests upon a strip firmly sustained and extending along underneath the strings. At one end is an elevated finger, *e*, which terminates in a 50 bend, to which is secured the node-producing stop or harmonic damper *S*, suspended just

over the string at the point where the harmonic node is desired. At the other end of this lever *l* is the depending finger *d*, terminating in a buffer, *x*. This buffer is struck 55 by the spring-strip *s*, secured to the end of the lever *L'*, and fitted with a thumb-screw, *t*, for adjusting its distance, as required, from the buffer-button beneath it upon the lever *L'*. The coiled spring *c* is designed for drawing its end of the lever *l* down when the hammer *h* drops from the string *w*, so as to lift the node-producing stop *S* from the string.

The lever *l* and its fingers *d* and *e*, with the node-producing stop *S* and buffer *x*, as well 60 as the springs *c* and *s*, are constructed of any desired material. The stop *S* and buffer *x* are faced, too, with any desired material, as is the buffer-button on the lever *L'* beneath the spring *s*. The relative lengths of the arms 70 of the lever *l* and the fingers *d* and *e* are determined by the relative position of the string and hammer and of the position desired for the harmonic node; so, too, the length and strength of the springs *c* and *s*.

75 With my invention embodied and combined with the hammer and key of a piano-string and their complementary levers, when the hammer *h* is thrown up by the pressure of the finger upon the key *a*, the spring *s* will operate the lever *l* so as to bring the node-producing stop *S* down upon the string just before it is struck by the hammer, and will hold it down upon the string until after the vibrating blow is struck by the hammer, the hammer striking the string at any desired point of either of the harmonic sections created by this stop *S*. The length of time which the stop *S* shall bear down upon the string is determined by the adjustment of the thumb-screw *t*.

80 With my invention constructed and operated as now described and illustrated the string may be of any desired length, providing it be an exact multiple of the harmonic section created by the node-producing stop. The string may therefore be made to provide 85 two or any greater number of similar harmonic sections or aliquot parts, the resolution of whose several vibrations shall give the 90 principal tone desired from the string. Similarly other resultant principal tones may be 95 100

elicited from the same string by locating at proper places along the string other node-producing stops operated by pedals or by additional banks of keys.

5 What I claim, and desire to secure by Letters Patent as my invention, is—

1. The combination, with the hammer or key of a piano, of a node-producing stop acting in connection with the key or hammer and so arranged that by the action of the key or hammer the stop will press upon the piano-string when the string receives the blow from the hammer, thus causing the string to give out one of its harmonic tones, and be re-
15 moved from contact with the string shortly

after the blow from the hammer has been delivered, substantially as and for the purpose hereinbefore described.

2. The combination of the lever *l*, with its fingers *d* and *e*, node-producing stop *S*, buffer *x*, springs *c* and *s*, thumb-screw *t*, and buffer-button, with the piano-string *w* and its hammer *h*, key *a*, and complementary levers *L L'*, substantially as and for the purpose hereinbefore described.

HARVEY WORRALL.
